SHORT-CIRCUITING DEVICE FOR ELECTRIC MOTORS

Stephen D. Hartog, Normandy, Mo., assignor to
William J. Peters

Application December 28, 1936, Serial No. 117,765

2 Claims. (Cl. 172—279)

This specification, aided by the accompanying drawing, discloses certain new and useful improvements in short-circuiting devices for alternating current motors.

5 The purpose and use of short-circuiting devices are well known and adequately described in the art to which such devices relate, and further reiteration would only be additional superusage except, briefly summarized, an electric 10 motor short-circuiting device or operating changing device is the means employed to convert an alternating current motor automatically from that of a repulsion starting condition to that of an induction running condition, and vice versa, 15 as the revolutions per minute of the rotor shaft increase or decrease.

The improvements hereinafter described and illustrated are primarily directed to simplification of construction employing few working parts 20 in the structure, improved means and mode of operation, reduced production cost, and a construction having the advantageous feature of a compact and complete assembly unit.

An object is to provide a short-circuiting device 25 centrifugally operated to effectuate instantly a make and break contact with the commutator, combined with a rolling action on the commutator within the sweep of the circuiters' motion.

30 Another object is to provide an electric motor short-circuiting or current-changing device in which the circuiters, while operating under centrifugal influence, move oscillatory with a cushioning smoothness superinduced by means of a 35 resilient spring pressure yieldingly operative on the circuiters at a position of maximum effectiveness; and a further object is to provide electric motor short-circuiters that engage and contact with the commutator at one position, then, upon 40 increasing speed, sweep to a different radial position, thus insuring a clean, bright electrical conducting surface on the face of the commutator and the short-circuiters.

Possessed of the capacity to fulfill such ends, 45 the invention consists in novel features of construction which embody a rotatable body having a peripheral contour providing means to engage short-circuiters for operative movement thereon, a plurality of short-circuiters mounted for operative movement and engagement on the peripheral contour of the expressed body, and means yieldingly operating upon the short circuiters.

For the purpose more clearly to understand the 50 embodied improvements constituting the inven-

tion, the following description is given, and, with the aid of the accompanying drawing, it is discernible:

Fig. 1 is an elevation in section of the commutator end of an electric motor. 5

Fig. 2 is an elevation in section of a portion of the commutator end of an electric motor.

Fig. 3 is an elevation in section of a portion of the electrical short-circuiting assembly unit.

Fig. 4 is a view in elevation of a circular or 10 garter spring member.

Fig. 5 is a face view of an apertured disc.

Fig. 6 is a fragmentary surface view in elevation.

Fig. 7 is a view in dotted outline illustrating the 15 manner in which the short-circuters are assembled on the rotatable body.

In the drawing, 10 designates the rotor shaft of an electric motor to which is attached a commutator hub 11 having a plurality of segmental 20 commutator bars 12 mounted upon its circumferential surface. Located adjacent the lateral face 13 of the hub 11 and in spaced relation therewith is that of a rotatable body denominated a flanged disc 14, having a central hub 15 and a rim 16 25 providing peripheral contours 17, 18 and 19.

Upon the rim surface thus provided, a plurality of segmental short-circuters 20 are mounted for operative movement. Formed upon the body of the short-circuters 20 and depending for 30 a limited distance therefrom are projecting portions 21 and 22 of which one portion 22 is provided with a claw or hook 23 which is adapted to engage the peripheral contour of the rim 16 at 19 in order to secure the short-circuters in 35 engaged position while in operation. The projecting portions 21 and 22 are spaced one from the other by an opening or cutout formed in the body 20 of the short-circuters to provide surfaces 24, 25 and 26 suitable for mounting the short- 40 circuiters 20 upon the peripheral contour of the rim 16.

The body 20 also has an additional opening or cutout in order to provide surfaces 27, 28 and 29. The surfaces thus provided and enumerated 45 constitute means contributory to the manner of assembling the short-circuters, their maintenance operatively, and their operative performance.

In the drawing (Fig. 7) there is shown the manner in which the short-circuters are assembled on the flanged disc 14. As shown, the short-circuter 20 is positioned longitudinally with its opening in line with the projecting rim 16, then turned clockwise until the surface 24 of the short-circuter is brought into contact with the surface 50 55

of the flanged disc 14 and the surface of the claw 23 in contact with the surface of the rim 19. The short-circuiter then assumes an upright or vertical position. Thus positioned, it is incapable of dislocation while in operation, and otherwise immovable other than in the direction to contact with the commutator 12. In the manner thus indicated, the short-circuiter 20 are assembled upon the peripheral contour of the flanged disc 14 in series, a definite number of which are assembled between spacers 30, portions which are pressed from and bent to a rectangular position, and projecting a limited distance from the plane surface of the flanged disc 14.

In the form and embodiment of the invention illustrated in Fig. 1, it is there shown that the flanged disc 14 is mounted securely on the rotor shaft 10, and that it is positioned in spaced relation to the commutator. The short-circuiter 20 are shown in an upright or vertical position, and they are sustained in that normal operative position by means of a resiliently yielding coil spring 31. The coil spring is shown to have one end face seated against the surface 28 of the short-circuiter, and the other end face abutting the wall face 13 of the hub 11.

In order to maintain the short-circuiter device in its proper position on the shaft 10, a channel 32 is formed in the shaft. The location of the channel in the shaft is such that one side wall 33 of the channel is in line with the face of the flanged disc 14. Into the channel thus formed and provided, an apertured disc 34, fitting tightly into the channel and pressed securely therein, arranges the entire unit in complete operative assembly. Thus equipped, the rotor shaft 10 when in action assumes certain speed revolutions per minute and, upon the attainment of a definite speed, the short-circuiter are impelled to action under centrifugal influence. The short-circuiter being so designed and constructed respond to the centrifugal influence by turning on their axis or pivot 35 (indicated in the drawing Fig. 1 and Fig. 3) under the cushioningly yielding influence of the spring 31 to contact with the commutator 12, thereby changing the electrical conditions of the motor. The initial contact of the short-circuiter upon the surface of the commutator is made at a position indicated at 36, then changing to a position indicated at 37, in consequence of increased speed. At the instance of reduction of the speed below definite revolutions per minute, the centrifugal influence is overcome by the pressure influence of the spring 31 and by means of which the short-circuiter are restored to their normal position.

In the view Fig. 2 of the drawing, a different form of spring is shown in assembly with the short-circuiter 20. The spring 31 is circular in form and exerts its influence in such a manner as to be diametrically expansive and contractive. The spring 38 is shown seated within the opening of the short-circuiter and bearing upon the surface 27, thereby sustaining the short-circuiter in contact with the peripheral contour 17 of the rim 16. When affected by centrifugal influence, the short-circuiter are drawn off their seat and instantly swept into contact on the face of the commutator 12 at a position indicated at 36 and, at the instance of increased speed, advance radially outward on the face of the commutator to a position indicated at 37. As the short-circuiter are advancing radially outward under centrifugal influence, their axis or pivot is act-

ing likewise and along the surface 24 of the projecting portion 21, their radial movement outward being limited as shown in dotted outline by the engagement of the claw 23 with the rim surface 19.

In the drawing, Fig. 3 is a view in section of a portion of the present short-circuiter device denominated an assembly unit. This construction provides for the employment (all other conditions being equal) of a disc 40 having a hub 41 apertured to fit tightly upon and be fixed to the surface of the hub 15. It is obvious that the disc 40 is employed to provide an abutment for the end face of the coil spring 31 and, in so doing, the device is complete as an assembly unit. This type of construction possesses an advantage in that it tends to facilitate transportation, replacement sales, and is appreciably economical and convenient in assembly with electric motors.

In order to comply with the statute, the invention has been described in language more or less specific as to structural features, it is to be understood that the invention is not limited to the specific details shown, but that the means and construction herein disclosed comprise the preferred form of several modes of putting the invention into effect, and the invention is, therefore, claimed in any and all of its forms and modifications within the legitimate and valid scope of the appended claims.

I claim and desire to secure by Letters Patent of the United States of America my invention which is:

1. In an alternating current motor having a commutator, a short-circuiter device for short-circuiting the commutator, comprising a hub-flanged disc having a peripheral contour terminating in a rim, a plurality of short-circuiter each having projecting body portions spaced one from the other by an opening therebetween, the opening therebetween providing the means whereby the short-circuiter are capable of being mounted for operative movement astride the peripheral contour of the hub-flanged disc, the short-circuiter thus mounted being capable of oscillatory movement upon the peripheral contour of the hub-flanged disc in a direction to and from the commutator only, means on the projecting body portions of the short-circuiter adapted to restrain their displacement while operative under centrifugal influence, and pressure means yieldingly operative upon and in contact with the short-circuiter, the named pressure means, having contact with the short-circuiter and localized between the short-circuiter's commutator contacting surface and the surface upon which the short-circuiter pivot.

2. In a short-circuiter device for electric motor commutators, the short-circuiter device comprising a rotatory support a series of commutator short-circuiter mounted upon the peripheral contour of the rotatory support, each short-circuiter having body portions providing projecting limbs, the projecting limbs of each short-circuiter being structurely capable of embracing the peripheral contour of the rotatory support in a way to enable the short-circuiter to form operative engagement upon the rotatory support while under the influence of centrifugal force and spring pressure means interposed between the short-circuiter and the radial face of the commutator yieldingly sustaining the short-circuiter in normal position upon the rotatory support.

STEPHEN D. HARTOG.
